UNITED STATES PATENT OFFICE

119,644

DESIGN FOR A THERMOSTAT

Roy M. Schultz, Chicago, Ill., assignor to Cook Electric Company, Chicago, Ill., a corporation of Illinois

Application January 8, 1940, Serial No. 89,348

Term of patent 7 years

To all whom it may concern:

Be it known that, I, Roy M. Schultz, a citizen of the United States, residing at Chicago, in the county of Cook and State of Illinois, have invented a new, original, and ornamental Design for Thermostats, of which the following is a specification, reference being had to the accompanying drawing, forming a part thereof.

In the drawing:

Figure 1 is a top plan view of a thermostat showing my new design;

Figure 2 is a front perspective view of the thermostat; and

Figure 3 is a bottom elevational view of the same.

I claim:

The ornamental design for a thermostat, substantially as shown.

ROY M. SCHULTZ.
